Stanley Grant, 2928 Preston Lane, Merrick, N.Y.

Filed Mar. 25, 1965, Ser. No. 84,442

Term of patent 14 years

(Cl. D33—6)

FIG. 1

FIG. 4

FIG. 2

FIG. 3

FIG. 8

FIG. 9

FIG. 10

FIG. 1 is a perspective view of a cosmetic vanity cabinet showing my new design;

FIG. 2 is a front elevational view of the cabinet;

FIG. 3 is a plan view of the cabinet;

FIG. 4 is an elevational view of the cabinet as seen from the righthand side of FIG. 2;

FIG. 5 is a rear elevational view;

FIG. 6 is a perspective view similar to FIG. 1 illustrating a pair of mirrored panels in the raised position;

FIG. 7 is a front elevational view with the mirrored panels raised;

FIG. 8 is a plan view of the cabinet shown in FIG. 6;

FIG. 9 is an elevational view of the cabinet as seen from the righthand side of FIG. 7; and

FIG. 10 is a rear elevational view.

Elevational views from the lefthand side of FIG. 2 and FIG. 7 would appear the same as FIG. 4 and FIG. 9, respectively.

I claim:

The ornamental design for a cosmetic vanity cabinet, substantially as shown and described.
